UNITED STATES PATENT OFFICE.

OLOF N. TEVANDER, OF CHICAGO, ILLINOIS.

CLOSURE.

1,200,669.

Specification of Letters Patent. Patented Oct. 10, 1916.

Application filed June 26, 1915. Serial No. 36,557.

To all whom it may concern:

Be it known that I, OLOF N. TEVANDER, citizen of the United States, residing at Chicago, in the county of Cook and State of Illinois, have invented a certain new and useful Improvement in Closures, of which the following is a full, clear, concise, and exact description, reference being had to the accompanying drawings, forming a part of 5 this specification.

My invention relates to closures and is of particular service when employed to cover milk bottles, though the invention is not to be restricted to this adaptation thereof. 15 The closure of my invention includes a skirted cap and a band engaging portions of the cap skirt. This band desirably includes a string, preferably non-metallic, and a fastener for holding ends of the string in 20 relation to maintain or complete the formation of the band. The string employed is desirably thicker than coarse sewing thread and the ends thereof desirably extend in opposite directions through a fastening clip, 25 the string being drawn taut by pulling upon its ends in opposite directions, before the clip is caused to hold both ends of the string in fixed relation. I do not wish to be limited, however, to a construction in which the ends 30 of the string are drawn in opposite directions in applying the same to the skirted portion of the closure. The skirt of the cap is desirably puckered or gathered at one or more places to form an outsetting ear or 35 ears provided for engagement with the string for holding the string and cap in relation.

In the preferred embodiment of the invention the band passes through the ears so 40 as to be completely encompassed by material of the closure to insure the position of the band with respect to the closure.

The closure of my invention is desirably applied to receptacles by the machine dis- 45 closed in my co-pending application Serial No. 36,556, filed June 25, 1915 (Case A).

I will explain my invention more fully by reference to the accompanying drawings showing the preferred embodiment thereof 50 and in which—

Figure 1 is a view in elevation of a milk bottle capped by the closure of my invention; Fig. 2 is a view on line 2 2 of Fig. 1; Fig. 3 is a view on line 3 3 of Fig. 2; and 55 Fig. 4 is a detail of the fastening clip.

Like parts are indicated by similar char-

acters of reference throughout the different figures.

The receptacle to which the closure is applied is shown as being in the form of a milk bottle 1 having the usual outsetting bead 2 at its mouth. The closure cap, formed of flexible material preferably paper, receives the neck portion of the bottle, the skirt of the cap being caused to underlie the bead or enlargement 2 in the process of the application of the cap to the bottle. The skirt is desirably made by forming the paper of the cap into folds as illustrated. A part or parts of the skirt having particularly large folds 3 formed therein constitute outsetting ears or projections. These ears or projections 3 are threaded, desirably at the middle of the skirt, by the band which is to maintain the cap and bottle in assembly, the part of the band which passes through the ears 3 being preferably the string portion 4 thereof. After the string portion of the band has been drawn sufficiently tight about the skirt of the cap to insure the maintenance of assembly of cap and bottle some fastening device is employed to hold the ends of the string in fixed relation.

In the preferred embodiment of the invention the ends of the string are drawn in opposite directions and are caused to overlap in the presence of the fastening device, which fastening device is preferably in the form of a clip 5 (preferably initially loose with respect to both ends of the string) which is clamped into engagement with the overlapping ends of the string by some suitable mechanism such as that illustrated in my said co-pending application. When the clip has thus been applied to the string the complete band, comprising the string and clip, is disposed below the outsetting bead 2 which overhangs the band to prevent it from being drawn over the mouth of the bottle. The ears, by being threaded by the band, prevent the band from being lowered from the cap without tearing the ears. When the ears are thus related to the band they constitute a seal structure to guard against the undetectable separation of the band from the cap.

While I prefer to employ fibrous string and bring it into such engagement with the ear formation upon the skirt of the cap that the shape of the band is not particularly modified at such ear formation, yet there

are characteristics of my invention which are not to be limited to such an embodiment thereof.

While I have herein shown and particularly described the preferred embodiment of my invention I do not wish to be limited to the precise details of construction shown as changes may readily be made without departing from the spirit of my invention, but

10 Having thus described my invention I claim as new and desire to secure by Letters Patent the following:—

1. A receptacle in combination with a closure including a skirted cap whose skirt 15 receives the receptacle and which cap is formed of flexible material, the skirt being formed into folds and having an outsetting ear formation projecting beyond these folds; a string surrounding the skirted portion of the cap and passing through said 20 ear formation and in tight engagement with

other folds; and a fastener uniting the adjacent ends of the string.

2. A receptacle in combination with a closure including a skirted cap whose skirt receives the receptacle and which cap is formed of flexible material; the skirt being formed into folds and having an outsetting ear formation projecting beyond these folds; a string surrounding the skirted portion of the cap and engaging said ear formation and in tight engagement with other folds; and a fastener uniting the adjacent ends of the string.

25 In witness whereof, I hereunto subscribe my name this twenty second day of June 30 A. D., 1915.

OLOF N. TEVANDER.
